CONVEYER SYSTEM

William J. Taylor, deceased, late of Syracuse, N. Y., by Ingeborg Taylor, administratrix, Syracuse, N. Y., and John E. Regan and Albert N. Klyver, Syracuse, N. Y., and Paul R. Kuhn, San Francisco, Calif., assignors to Lamson Corporation, Syracuse, N. Y., a corporation of New York

Original application April 29, 1939, Serial No. 270,728. Divided and this application December 29, 1941, Serial No. 424,816

1 Claim. (Cl. 193—20)

This invention relates to an improvement in conveyor systems, and more particularly to an improvement in the loading mechanism by which loads are supplied to and properly centered upon a vertically traveling elevator carriage. The present application is a division of our copending application Serial No. 270,728, filed April 29, 1939, now Patent No. 2,270,357, issued Jan. 20, 1942.

The primary object of this invention is to provide a loading mechanism comprising a platform over which the loads, usually in the form of tote boxes, are advanced, a plurality of movable stops by which the advance of the loads is checked, and devices so connected with the stops that the simultaneous tripping of certain devices by a load causes the stops to move out of checking position and allow the load to advance past such stops.

This and other objects of the invention will appear from an examination of the following description and of the accompanying drawings which form a part thereof, and in which

Fig. 1 illustrates in side elevation a loading platform embodying this invention;

Fig. 2 is a plan view of such platform with the carriage positioned therein;

Figs. 3, 4 and 5 are side elevations, on larger scale, of portions of the platform, being taken along the lines 3—3, 4—4 and 5—5 respectively on Fig. 2;

Fig. 6 is an enlarged cross-sectional view taken along the line 6—6 on Fig. 2; and

Figs. 7 and 8 are a diagrammatic plan view and a wiring diagram respectively illustrative of the mode of operation of the load-checking stops.

Each loading station 100 comprises a frame formed by vertical beams 101 extending from the floor and suitably located crossbeams 102. This frame forms a vertical well provided with vertical tracks 104 on which travels intermittently an elevator carriage 105. The elevator carriage is operated by a motor (not shown) through chains 108, one end of each chain 108 being attached to the carriage 105. The elevator carriage 105 comprises a transverse beam 115, uprights 116 fixed at the ends of the beam 115, and a platform 117 formed by longitudinally extending beams 118 supported upon a transverse beam 119 resting on the beam 115 and secured to said beams 119 and 115 by angle bars 120 and braces 121.

At the bottom of the well is mounted an inwardly inclined loading platform 130 by which loads are delivered to the platform 117 of the elevator carriage. The loading platform 130 comprises six sections arranged in two groups of three sections each and suitably spaced apart to permit

the beams 115 and 118 of the carriage to pass freely between the groups. Each section includes freely rotatable rollers 131 over which the load travels, said rollers being mounted in U-shaped strips, the outer leg of the strip on each outer section being extended to form a load guide 132.

The loads supplied to the elevator carriage are usually in the form of tote boxes which vary in size and for convenience have been divided into three classes. In order to ensure that the boxes are properly positioned upon the carriage certain means are employed. The boxes are supplied from the right side of the well, as shown in Fig. 1. The sections at the left carry stops by which the boxes are centrally positioned longitudinally. Such stops are divided into three classes, stationary stops 135, movable roller stop 136 and movable roller stops 137. The stop 136 includes an arm 140 pivotally mounted intermediate its ends and a solenoid 141, the stop being normally in the raised operative position as shown in Fig. 4 and depressed when the solenoid is energized. Each stop 137 similarly includes a pivotally mounted arm 142 and solenoid 143 and is depressed when the solenoid is energized.

Suitably located in the loading platform are a plurality of circuit makers designated 150, 151, 152, 153 and 154, each provided with an arm tripped by a tote box passing thereover. The circuit maker 150 is of the single type including normally open contacts. The normally open contacts of circuit maker 150 are in series with the normally open contacts of circuit maker 154 and when these circuit makers are tripped simultaneously by a load the solenoid 141 is energized to depress the stop 136. The normally open contacts of circuit maker 151 are in series with the normally open contacts of circuit makers 152 and 153, and when these three circuit makers are tripped simultaneously by a load the solenoids 143 are energized to depress the stops 137.

The loading operation will be considered with reference to the three sizes of tote boxes. The stops 136 and 137 are normally in the position shown to check the movement of the tote boxes. The successive tripping of circuit makers 150 and 151 by the smallest box has no effect upon the positioning features under consideration. This box, however, advances against the stops 137 and holds the circuit makers 152, 153 and 154 tripped. The medium sized box trips the circuit maker 150 without effect but is large enough so that it simultaneously trips the circuit makers 151, 152, 153 and 154 which cause the depression of the stops 137 and allow the box to advance into

contact with the stop 136, and hold the circuit makers 152, 153 and 154 tripped. The largest box is of such size that it trips all the circuit makers simultaneously, whereupon the circuit makers 151, 152 and 153 coact to cause the depression of the stops 137, and the circuit makers 150 and 154 coact to cause the depression of the stop 136 so that the box advances over the depressed stops 136 and 137 into contact with the stationary stops 135 and holds the circuit makers 152, 153 and 154 tripped.

The central positioning of the boxes laterally is controlled by the guides 132 and also by the circuit makers 152 and 153. As pointed out above, these circuit makers are in series at all times, and unless a box is so positioned that it trips these circuit makers simultaneously, the energizing relay circuit cannot be closed and the elevation of the carriage will not be initiated.

While one embodiment of the invention has been shown and described, it will be understood that it is not limited thereto and that other embodiments thereof may be made without departing from the spirit and scope of the invention as set forth in the following claim.

We claim:

In a conveyer system, a platform over which articles are advanced in one direction, stops for limiting the advance of said articles, certain of said stops being stationary and other of said stops being movable into and out of operative position, the movable stops being normally in the operative position and ahead of the stationary

stops, control devices positioned and arranged to be tripped by the articles as they are advanced, and connections between said devices and said movable stops, the stationary stops being arranged in a row across the path of travel of the articles and the movable stops being arranged in two parallel planes extending transversely of the length of the platform and at different distances respectively from the row of stationary stops and the control devices being spaced along such path of travel so that the number of devices which will be simultaneously tripped depends upon the sizes of the articles, the parts being so constructed and arranged that the simultaneous tripping of certain control devices by an article of one size moves the movable stops in the transverse plane farthest from the row of stationary stops into inoperative position and allows the article to advance past such stops into contact with a stop in the transverse plane nearest to the fixed stops, and the simultaneous tripping of the same and other control devices by an article of a greater size will move the movable stops disposed in both of said transverse planes into inoperative position and allow said larger article to advance past all of the movable stops and into contact with the row of stationary stops.
